UNITED STATES PATENT OFFICE.

ROBERT CHARLES MENZIES, OF SCHENECTADY, NEW YORK.

SOAP-SUPPLYING DEVICE FOR GLASS-WASHERS.

1,174,336.

Specification of Letters Patent.

Patented Mar. 7, 1916.

Application filed February 27, 1915. Serial No. 10,989.

To all whom it may concern:

Be it known that I, ROBERT C. MENZIES, a citizen of the United States, residing at Schenectady, in the county of Schenectady 5 and State of New York, have invented a new and useful Soap-Supplying Device for Glass-Washers, of which the following is a specification.

The present invention appertains to a device for supplying water containing soap or other cleansing agent to a device for washing or cleaning glasses, tumblers, or the like.

The object of the invention is to provide a 15 device adapted to be interposed in a water line or pipe, and adapted for applying soap or a cleansing agent to the water passing therethrough.

It is also within the scope of the invention to provide an appliance of the nature indicated and embodying the features above noted, which appliance is comparatively simple and inexpensive in construction, as well as being convenient, practical and efficient in use.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a view illustrating the apparatus, parts being shown in section, and 40 parts being broken away. Fig. 2 is a cross section of the soap supplying device, taken on the line 2—2 of Fig. 1.

The soap supplying device, which is adapted to be interposed in the water line 45 or pipe, embodies an upright cylindrical casing 1, having a convex bottom 2, and concaved top or upper end 3. The top or upper end 3 of the casing or tank 1 is provided at one side of its center with a filling 50 opening 4, which is normally closed by a screw plug or cap 5 that may be removed for filling the tank with powdered soap or an equivalent cleansing agent.

The tank 1 is provided with a lower inlet, 55 consisting of an inlet member 6 threaded or otherwise engaged through one side of the

tank 1 adjacent the bottom or lower end 2 of the tank, and the inner end of the member 6 is provided with an outlet nipple 7 turned or curved to one side. The water inlet pipe 8 is threaded or otherwise engaged into the member 6, and supplies water into the tank 1 through the member 6 and its nipple 7. The nipple 7 will direct water around the walls of the tank 1, whereby the 60 water will have a whirling or spiral motion when passing from the lower end to the upper end of the tank, to thereby agitate the contents of the tank.

Threaded or otherwise engaged through 70 the central portion of the top 3 of the tank, is a tubular member or sleeve 9, having a depending perforated nozzle 10 within the tank, and an outlet pipe 11 for the tank 1 is threaded or otherwise engaged to the upper end of the tubular member or sleeve 9. The apertured or perforated nozzle 10 depends centrally or axially within the tank 1, and the apertures thereof are restricted to prevent the excessive flow of the particles 75 of soap or cleansing agent therethrough from within the tank.

The pipe 11, together with the pipe 8, provides a water supply line in which the tank or casing 1 of the soap supplying device is interposed, and the pipe 11 extends to a controlling or regulating valve 12. A clear water pipe 13 is also connected to the valve 12, and an outlet pipe 14 extends from the valve 12 to an ordinary glass washer 80 15. The glass washer 15 may be of any suitable type, and is adapted for receiving a tumbler, glass or other article for purpose of cleansing the same by means of a rotary brush and a stream of water forced against 95 the glass or other article. It will of course be understood that the pipe 14 may extend to any suitable device or contrivance for utilizing the soapy water for cleansing purposes.

The three-way valve 12 embodies a casing 16 having the ports 17, 18 and 19 into which the ends of the respective pipes 11, 13 and 14 are engaged. A rotary spigot 20 is journaled within the casing 16 and the ports 100 17, 18 and 19 extend to the spigot. The spigot is provided with a lateral or transverse passage 21 therethrough which is of such shape as to bring the ports 17 and 18 into communication with the port 19, and 105 whereby the spigot 20 may be utilized for controlling the amount of water flowing

from each of the pipes 11 and 13 through the valve to the pipe 14. The spigot 20 may be provided with a handle or other suitable device 22 for swinging the spigot properly.

In operation, the powdered or granulated soap, or equivalent cleansing agent, is introduced into the tank 1 through the opening 4 when the plug or cap 5 is removed, and 10 then after the plug or cap is reapplied to the tank, the water may be allowed to flow into and through the tank 1 from the pipe 8. When the apparatus is not in use, the port 19 may be closed to thereby close the 15 passage through the pipe 14, by swinging the spigot 20 properly, and when the spigot is swung to the position as illustrated in Fig. 1, it will bring the pipes 11 and 13 into communication with the pipe 14 so as allow 20 the water to flow from each of the pipes 11 and 13 into the pipe 14 and to the washer 15. The water in passing through the tank will have a whirling motion therein, to agitate the soap or cleansing agent, and the 25 water will dissolve a portion of the soap or cleansing agent and carry the same therewith into the pipe 11. Clear water is supplied through the pipe 13 to the valve 12, while the soapy water is supplied through 30 the pipe 11 to the valve 12, and by controlling the spigot 20 it is possible to vary the proportions of clear and soapy water admitted to the pipe 14, in order that the proportion of soap or cleansing agent contained in the water delivered through the 35 pipe 14 to the washer 15 will be as desired. It is evident, also, that the spigot 20 may be swung to close either of the ports 17 and 18, but to leave one or the other of the pipes 40 11 and 13 in communication with the pipe 14. Thus, when the port 17 is closed with the pipes 13 and 14 in communication, clear water will be delivered to the washer, whereas if the port 18 is closed, with the pipes 11 45 and 14 in communication, the soapy water from the tank 1 will be supplied, without being diluted by the clear water, to the washer. The spigot 20 may thus be controlled for either cutting off the flow of 50 water to the pipe 14, or stopping the flow of water from either of the pipes 11 and 13, and for regulating the amount of water flowing from the pipes 11 and 13 into the pipe 14. It is thus possible for the operator to regulate the apparatus so that the water delivered to the washing device will

contain the proper amount of soap or cleansing agent to effectively wash or clean the glasses, milk bottles or other articles, and to prevent the same being soaped excessively. The advantages of supplying soap or other cleansing agent to the water will be obvious, since it will increase the efficiency of the washer, as over the mere use of clear water, as is ordinarily done.

Particular attention is directed to the fact that the nipple 7 causes the water to have a whirling motion within the tank, and due to centrifugal action the cleansing agent will be carried around the walls of the tank. The cleansing agent is thoroughly agitated and mixed with the water, and at the same time, the body of the cleansing agent is moved away from the nozzle 10 to prevent the excessive discharge of the cleansing agent. The whirling motion of the water will thus raise the cleansing agent and carry it around the walls of the tank, agitating the agent thoroughly, and the water in reaching the upper end of the tank will flow inwardly and thence through the apertures of the nozzle. The provision and location of the nozzle 10 is therefore of importance in connection with the nipple 7.

Having thus described the invention, what is claimed as new is:

1. A device of the character described, comprising a tank having a lower water inlet member at one side provided with a nipple turned to one side to give the water an upward whirling motion within the tank, and the tank having an upper central depending perforated nozzle forming an outlet therefor.

2. In a device of the character described, a tank for holding a cleansing agent, a water supply pipe connected to one side of the tank adjacent the lower end thereof for delivering water into the tank and giving the water an upward whirling motion, a central depending perforated nozzle carried by the upper end of said tank, and piping connected to said nozzle and having a controlling valve therein.

In testimony that I claim the foregoing as my own, I have hereto affixed my signature in the presence of two witnesses.

ROBERT CHARLES MENZIES.
